UNITED STATES PATENT OFFICE.

CHARLES BOCCIA, OF NEW YORK, N. Y.

DESIGN FOR A TOOTH-BRUSH.

48,666.

Specification for Design.

Patented Mar. 7, 1916.

Application filed October 23, 1915. Serial No. 57,613. Term of patent 14 years.

To all whom it may concern:

Be it known that I, CHARLES BOCCIA, a citizen of the United States, residing at New York, in the county of New York and State of New York, have invented a new, original, and ornamental Design for Tooth-Brushes, of which the following is a specification, reference being had to the accompanying drawing, forming part thereof.

The figure is a perspective view of the tooth brush illustrating my new design.

I claim:

The ornamental design for a tooth brush, as shown.

CHARLES BOCCIA.

Witnesses:

ANNA V. DOYLE,
GEO. A. BYRNE.
